UNITED STATES PATENT OFFICE.

ETHEL E. MILLER, OF CLEVELAND, OHIO.

AERIAL TOP.

1,270,313.

Specification of Letters Patent. Patented June 25, 1918.

Application filed September 21, 1917. Serial No. 192,565.

To all whom it may concern:

Be it known that I, ETHEL E. MILLER, a citizen of the United States, residing at Cleveland, in the county of Cuyahoga, State 5 of Ohio, have invented certain new and useful Improvements in Aerial Tops; and I do hereby declare the following to be a full, clear, and exact description of the invention, such as will enable others skilled in the art 10 to which it appertains to make and use the same.

This invention relates to tops and is directed more particularly to what may be aptly termed an aerial top.

15 An object of the present invention resides in the provision of a top including a top and means coöperating in novel manner with the top to impart to the latter a rotary impulse, said top being so constructed as to rise and 20 sail through the air and remain suspended until its weight overcomes the resistance offered by the air, whereupon it will gradually fall, and, alighting upon the ground will continue to spin until the rotary impulse 25 ceases.

With the above and other objects of similar nature in view, the invention consists in the construction, combination and arrangement of parts set forth in and falling within 30 the scope of the appended claim.

In the drawing,

Figure 1 is a side elevation of the invention, illustrating the position of the parts prior to rotating the top,

35 Fig. 2 is a vertical section therethrough, and

Fig. 3 is a perspective view of the top.

Referring now more particularly to the accompanying drawing, the invention comprises generally speaking a top A, and means 40 designated at B for imparting to the top a rotary impulse.

Specifically, the top A is preferably stamped from a single blank of sheet material and includes an annular rim 5, a central portion 6, and radially extending propeller blades 7 connecting said rim and central portion. The central portion 6 of the top is depressed in any desired manner to 45 provide a tapered socket 8 of substantially conical formation, the apex 9 of the cone constituting a suitable point upon which the top 5 is spun by manipulation of the spinner B above referred to. The blades 7 of the 50 top are preferably constructed as shown and are similarly disposed at an incline like the

blades of an ordinary propeller so that upon rotation of the top the blade will impinge on the air, thereby raising the top and causing the same to sail through the air. It is 60 understood that the top will remain suspended until its weight overcomes the resistance offered by the air, whereupon it will gradually fall and, alighting upon the point 9, will continue to spin until the rotary impulse ceases.

Referring now to the spinner B through the medium of which a rotary impulse is imparted to the top, the same consists of a tubular handle 10 having mounted and suitably secured therein a coil of wire 10' providing a plurality of spiral convolutions as clearly shown in Fig. 2. Slidably mounted in the handle 10 is a plunger stem 11 provided adjacent its inner end with a lug or 70 projection 12 engaging the convolutions of the wire whereby a thrust upon the handle, to move it longitudinally of the stem, will impart to the latter a rotary impulse. A cap 13 is provided to close the open end of 75 the tube and prevent complete withdrawal of the stem therefrom. Fixed in any suitable manner upon the end of the stem is a circular disk 14 of fiber or other relatively hard, wear resisting material. The circular 80 disk 14 is beveled at its edge to frictionally wedge in the tapered socket 8 formed by the hollow in the central portion 6 of the top. It will be seen that when the spinner is used 85 and the disk 14 engaged in the socket 8 a positive frictional engagement is had between the spinner and the top without regard to the perpendicular position of the spinner or the annular disposition thereof 90 when the top and said spinner are in use.

In the operation of the device, to spin the top, the stem is withdrawn from the handle to its full extent and the latter grasped and held vertically with the disk 14 engaged in the socket 8 of the top. A rapid downward 95 thrust is then given to the handle to rotate the stem, and the movement is imparted to the top through the medium of the disk 14. The spinner B is then quickly removed from the top whereupon the same will rise and 100 sail a considerable distance through the air, after which it will again fall as previously described.

What I claim is:

The combination of a wheel body forming 110 a top having a central hollow conical portion constituting a boss providing at its apex a

spinning point, spinning means for imparting a rotary impulse to the top and having a plunger, a fibrous circular disk on the end of the plunger and having a beveled edge to 5 frictionally wedge in the hollow in the conical boss, and radial wings on the body concentrically of the boss.

In testimony whereof I affix my signature in the presence of two witnesses.

ETHEL E. MILLER.
